UNITED STATES PATENT OFFICE.

LEO F. ADT, OF ALBANY, NEW YORK.

EYEGLASS-MOUNTING.

1,095,367.

Specification of Letters Patent.

Patented May 5, 1914.

Application filed March 23, 1910. Serial No. 551,049.

To all whom it may concern:

Be it known that I, LEO F. ADT, of Albany, in the county of Albany and State of New York, have invented certain new and useful Improvements in Eyeglass-Mountings; and I do hereby declare the following to be a full, clear, and exact description of the same, reference being had to the accompanying drawings, forming a part of this specification, and to the reference-numerals marked thereon.

The present invention relates to eyeglass mountings particularly of the finger-piece type in which the guards are moved toward the nose under the action of individual springs, and an object of the invention is to provide a construction in which the springs are protected and hidden from view from the front of the mounting.

Another object is to provide a construction in which the springs will be retained in place and under tension when the guards are removed from the mounting for repair or other purposes and in which the springs may similarly be removed without disturbing the other parts.

Still another object is to provide means for adjusting of the tension of the springs so that the pressure of the guards on the nose may be varied.

To these and other ends the invention consists in certain improvements and combinations of parts all as will be hereinafter more fully described, the novel features being pointed out in the claims at the end of the specification.

In the drawings:—Figure 1 is a front view of a mounting constructed in accordance with the present improvements, one of the guards and its spring being removed: Fig. 2 is a plan view of the mounting with one of the guards removed and its spring held to the mounting under tension: Fig. 3 is a bottom view of the mounting with one of the guards removed: Fig. 4 is a transverse section on the line *a—a*, Fig. 2, and Fig. 5 is a rear view of a portion of the mounting in proximity to one of the guards.

In the embodiment of the invention herein illustrated the support comprises preferably an arch or bridging portion 1 for resting upon the nose, lens attaching devices 2 for securing the lenses 3, and shanks or connecting portions 4 between the bridging portion and the lens attaching devices.

The guards swing on the support preferably on the upper side thereof and each preferably embodies a nose engaging member having an upper pad 5 and a lower pad 6 supported at the rear end of a lever 7. The lever extends transversely of the plane of the lenses held by the support, and has at its forward end a finger piece or operating portion 8 which is bent downwardly at 9 in front of the support. In order that the guards may have swinging or pivotal action the shanks or connecting portions 4 of the support carry screws which project above and below the support, the upper end of each being provided with a head 10 for co-operation with the upper surface of a guard lever, and with a bearing 11 engaged by a laterally opening recess or bearing in a guard lever which also turns in engagement with the upper surface of the connecting portion 4. A shoulder 12 is preferably provided on the screw to engage the upper surface of the connecting portion and prevent the clamping of the guard by the screw.

The guards in this instance are moved toward the nose under the action of coiled springs 13. These springs are preferably arranged within pockets 14 formed on the under side of the support about the depending portions 15 of the screws, said depending portions being surrounded by the coils of the spring. Each spring may have an arm 16 extending into connection with its guard and for this purpose the front wall 17 of the pocket 14 may be provided with a horizontal slot 17 through which the arm 16 extends into engagement with the depending portion or finger piece 8 of the guard, the latter serving to hide the slot. To the end that the spring arm may enter the slot 17 each pocket may be provided with a vertical slot 18 connecting with the horizontal slot 17 and opening at the bottom of the pocket. Each spring arm 16 when disengaged from its guard, may be engaged with a shoulder 19 formed by notching a pocket at the inner end of its slot 17. The purpose of this arrangement is to retain the spring on the support under tension when its guard is removed from the support.

Owing to the fact that the springs of eyeglass mountings of this type must necessarily be small in order to provide an inconspicuous structure, great difficulty has been experienced in maintaining proper ten-

2

sion in the springs, and this is especially true of springs of helical formation arranged with their axes coincident with the turning axes of the guard. With the object 5 in view of overcoming this objection provision has been made in this invention for varying the tension of the guard positioning springs. Preferably this result is effected by providing a plurality of shoulders 10 on the support for engagement by the end 21 of the spring, these shoulders being formed in this instance by notching the rear wall of the pocket thereby rendering them invisible from the front of the mounting. 15 To remove the mounting from the nose or to place it thereon, it is merely necessary to press the finger pieces 8 toward each other, thus separating the nose bearing portions in rear of the support. When the finger 20 pieces are released, the nose bearing portions move toward each other under the action of the springs 13. The guard may be detached by disengaging the spring arm 16 from the finger pieces 8 being held in engagement 25 with the bearing 11 by the action of the spring. The springs may now be removed or held to the support by engaging the arms 16 with the shoulders 19. To vary the tension of the springs the arms 21 are engaged 30 with the proper shoulders 20.

An eyeglass mounting constructed in accordance with this invention has its springs so arranged that they are invisible from the front of the mounting and, in the present 35 embodiment, act to retain the guards on the mounting by continuously urging them into their bearings; but are detachable from the mounting, provision being made by which they may be retained upon the mounting 40 when the guards are removed and it will be further noted that in detaching the spring over the free ends of their centering projections as constituted by the screws or pivots, neither the latter nor the guard are necessarily disturbed in their positions. Conversely, the guard alone or both the guard and the pivot may be removed without detaching the spring or greatly disturbing it beyond slightly reducing its tension which 45 latter is still sufficient to hold it in place. The tension of the spring may be adjusted to vary the pressure of the guards upon the nose.

What I claim is:

55 1. In an eyeglass mounting, the combination with a support and a finger piece guard lever mounted to turn thereon, of a spring for positioning the guard and a housing formed independently of the guard lever 60 surrounding and concealing the spring, said housing embodying a wall interposed between the guard lever and the spring.

2. The combination with a support for the lenses having pockets on one side thereof, of finger piece nose guards mounted to

turn on the other side of the support, and coil springs arranged in the pockets and acting upon the guards.

3. The combination with a support for the lenses having pockets on the under side thereof, of finger piece nose guards mounted to swing on the upper side of the support, and coil springs mounted in the pockets and acting upon the guards.

4. In an eyeglass mounting, the combination with a support and a finger piece guard lever mounted to turn thereon of a pivot for the guard rigidly connected to the support and provided with a shoulder between which and the support the guard turns, a housing surrounding one end of the pivot and a spring for positioning the guard coiled about the pivot within the housing.

5. The combination with a support for the lenses having a pocket in one side thereof, and a screw passing through the support from the opposite side thereof, having a head at its outer end, a bearing portion adjacent to the head and a screw portion engaging the support, of a finger piece nose guard mounted to turn on the bearing portion, and a coil spring arranged in the pocket about the screw and arranged to act upon the guard to move the latter.

6. In an eyeglass mounting, the combination with a support and a finger piece guard lever mounted to turn thereon, of a coil spring for positioning the guard and a housing surrounding and concealing the spring and provided with an opening, one end of the spring being extended through the opening in a direction transversely of the axis of the coil to coöperate with one of the first mentioned parts.

7. In an eyeglass mounting, the combination with a support and a finger piece guard lever mounted to turn thereon, of a housing on one of said parts having an open end and a slotted wall at its opposite closed end, and a coil spring arranged in the housing with one end arranged to act upon the latter at the open end and the other end thereof extended through the slot into coöperation with the other member.

8. The combination with a support for the lenses having pockets in one side thereof provided with openings in their front walls, of finger piece nose guards mounted to swing on the other side of the support and having portions extended vertically to cover the openings in the pockets, and springs arranged in the pockets and having arms extending through the openings into engagement with the guards.

9. In an eyeglass mounting, the combination with a support and a finger piece guard lever mounted to turn thereon, of a housing on one of said parts having an open end and a slot in a side wall adjacent to its opposite closed end, said housing being further

provided with a slot extending from the first mentioned slot to the open end of the housing and a detachable coil spring arranged in the housing to be inserted and removed through the open end thereof, one end of the spring being extended through the first mentioned slot to coöperate with the other member and being adapted to traverse the last mentioned slot when the spring is inserted or removed.

10. The combination with a support for the lenses having a pocket in the under side thereof provided with a vertical slot leading from the lower end of the pocket and a horizontal slot at the upper end of the vertical slot, of a finger piece nose guard mounted to turn on the upper side of the support, and a coil spring arranged in the pocket and having an arm operating in the horizontal slot and arranged to act upon the guard.

11. In eyeglasses, the combination of a pivotally-mounted lever, a spring for restraining said finger piece guard lever, and a casing inclosing said spring, said casing having a plurality of separate points of anchorage for one end of said spring.

12. The combination with a support for the lenses having a pocket therein provided with a plurality of notches, of a finger piece guard lever mounted to swing on the support, and a coil spring mounted in the pocket and having one end arranged to act upon the guard and the other end adapted to engage in any one of the notches.

13. The combination with a support for the lenses having a pocket in its under side, the rear wall of the pocket being provided with a plurality of notches and the front wall having a vertical slot opening at the bottom of the pocket, a horizontal slot meeting the upper portion of the vertical slot at one end and a notch at the other end of the horizontal slot, of a screw having a bearing portion projecting above the support and a portion arranged in the pocket, a finger piece guard lever mounted to turn on the upwardly projecting portion of the screw, and a coil spring surrounding the portion of the screw in the pocket and having one end engaging in one of the notches in the rear wall of the pocket and the other end operating in the horizontal slot and arranged to act upon the guard.

14. The combination with a support for the lenses, and a finger piece nose guard mounted thereon, of a spring for positioning the guard coiled about the axis thereof, and means for varying the tension of the spring.

15. In an eyeglass mounting, the combination with a support for the lenses and a finger piece nose guard mounted to swing thereon substantially in a horizontal plane and having an operating portion at the

front of the support, and a spring for positioning the guard, of means for securing one end of the spring at any one of a plurality of points about the axis of the spring for the purpose of varying the tension of said spring.

16. The combination with a support for lenses, and a finger piece nose guard mounted to turn thereon, of a coil spring for positioning the guard, and a plurality of shoulders with any one of which an end of the spring is adapted to be engaged to vary the tension of the spring.

17. The combination with a support for the lenses comprising a bridging portion, a lens attaching device and a horizontal portion connecting the lens attaching device and the bridging portion and provided with a vertically arranged opening, of a headed fastener passed through the opening projecting from opposite ends thereof and provided with a shoulder engaging the connecting portion, a finger piece nose guard turning on the fastener in engagement with the head and the connecting portion, a coil spring surrounding the other projecting portion of the fastener on the opposite side of the connecting portion and having one end arranged to act upon the guard, and means for adjusting the other end of the spring to vary the tension of said spring.

18. In an eyeglass mounting, the combination with a support and a finger piece guard lever mounted to turn thereon, of a housing having one end disposed toward the lever and a spring for positioning the guard adapted to be inserted in and removed from the housing through the other end thereof.

19. In an eyeglass mounting, the combination with a support and a finger piece guard lever arranged to swing in a horizontal plane, of a pivot for the guard removable from the support, a vertically extending centering projection on one of the parts and a coil spring for positioning the guard encircling the projection and removable therefrom without removing the guard or its pivot.

20. In an eyeglass mounting, the combination with a support and a finger piece guard lever, of a pivot for the guard removable from the support and a coil spring for positioning the guard encircling the pivot and removable therefrom without removing the pivot.

21. In an eyeglass mounting, the combination with a support, a finger piece guard lever and means for pivotally securing the guard on the support, of a coil spring for positioning the guard located to one side of both the guard and support and having its ends acting upon them respectively and a centering projection extending through the coil of the spring having one end supported

1 by one of the parts and a free end adapted to permit the independent removal and replacement of the spring over the same without releasing the guard.

5 22. In an eyeglass mounting, the combination with a support and a finger piece guard lever mounted to turn thereon, of a spring for positioning the guard carried by one of said parts and means coöperating 10 with each end of the spring to hold it under tension independently of the other part.

23. In an eyeglass mounting, the combination with a support and a finger piece guard lever mounted to turn thereon, of a 15 spring for positioning the guard carried by one of said parts with one end coöperating therewith and the other normally coöperating with the other part and means on said first mentioned part with which said last mentioned end of the spring may be engaged to 20 maintain the spring under tension on said part when the parts are separated.

24. The combination with a support for the lenses and a finger piece nose guard 25 mounted to swing thereon, of a spring for the guard detachably supported on the support and detachably engaging the guard, and a device on the support with which the spring is adapted to be interlocked to hold 30 it under tension when it is disengaged from the guard.

25. The combination with a support for

35 the lenses having a pocket in the under side provided with a horizontal slot and a finger piece nose guard mounted to turn on the upper side of the support, of a spring arranged in the pocket and having an arm operating in the slot and detachably engaging the guard, and a shoulder on the support with 40 which the spring arm is adapted to be engaged when disengaged from the guard so that the spring may be held under tension.

45 26. In an eyeglass mounting, the combination with a support, a finger piece guard lever pivoted to turn with one side against the support, and means for securing the lever on the latter comprising a part engaging upon the other side thereof to constitute a rigid bearing surface preventing axial movement, of a coil spring for positioning the guard located to one side of all the beforementioned parts, and a centering projection extending through the coil of the spring having one end supported by one 50 of the parts and a free end adapted to permit the independent removal and replacement of the spring over the same without disturbing the bearing surfaces confining the guard lever.
